PRINTING PLATE

Ernest S. Ballard, Berkeley, Calif., assignor to
Standard Process Corporation, Chicago, Ill., a
corporation of Delaware

Original application December 12, 1927, Serial No.
239,388. Divided and this application October
21, 1931, Serial No. 570,221

6 Claims. (Cl. 101—127)

This invention relates to printing surfaces and to a novel method of printing.

Intaglio printing surfaces heretofore generally used have been prepared from half-tone photographic negatives of the matter to be printed. Such negatives are utilized in reproducing on sensitized carbon or equivalent tissue the image of the negative of the matter to be formed on the plate. Such tissue is transferred to a copper or similar cylinder or surface and developed in the usual manner. Etching of the gelatine resist results in a printing surface in which the high lights are represented by minute ink receiving cells, the middle tones by larger cells and the shadows by still larger cells. The depth of such cells varies widely and the quantity of ink retained in the cells, after passage of the doctor blade, varies correspondingly so that the tone value of the printed matter is in very large measure dependent on the depth of the cells.

This invention aims to improve the art of printing by controlling the tone values solely by the area of the cells from which the ink flows to the surface being printed to the end that the ink may be caused to flow through the plate rather than applied to the cells externally as is customary.

Another primary object of the invention is to produce a printing plate having a multiplicity of minute separate and distinct ducts graduated in area to produce tones and shadows through which or from which the ink is supplied to the material or surface being printed.

Further objects of the invention will appear as a description thereof proceeds with reference to the accompanying drawing in which:

Figure 1 shows a view of a portion of a plate, illustrating how the dots may be arranged there-in to produce the desired lights and shades.

Figure 2 shows a magnified view of a portion of a screen positive used in the production of the plate.

Figure 3 shows a similar view of a portion of a screen negative employed in the method.

Figure 4 shows a longitudinal sectional view through a cylinder over which is arranged a printing plate embodying my invention.

Figure 5 is a transverse sectional view through the parts appearing in Figure 4.

Like reference characters indicate like parts throughout the several figures.

Typographic and pictorial printing processes as now operated have one common characteristic in that the ink is applied to the printing form from without, either by means of distributing

rollers passing over the printing forms or by revolving in contact with the printing cylinder. Or the printing cylinder, as in the case of intaglio machines, may revolve in a trough of ink, the surplus ink being removed from the cylinder by a flexible steel scraper known as a "doctor blade".

Application of the ink by exterior means involves difficulties and complications, as well as waste of material and labor. Where a "doctor blade" is employed, the constant friction against the cylinder frequently damages the printing surface.

This wearing of the printing surface is especially objectionable where large jobs are under way. The worn printing surface has to be replaced in the middle of the job, and there is no certainty that it will conform exactly to the initial surface.

This invention is intended to overcome all these troubles by bringing the ink from behind the plate, and directly through it, using minute ducts or holes in the plate to allow a percolating effect to occur. These extremely small ducts are graduated in size, where pictures are to be printed, and by virtue of these varied sizes produce shadows, half-tones and high lights in the printing process. Thus these ducts take the place of the printing dot in half-tone printing, and perform the office of the cells of varying depth as found in "Rotogravure" printing. However, the graduated tone effect depends not only upon the actual size of the dot, but in the difference in the rate of ink flow as affected by the frictional area of the sides of the dot. The area of the ducts varies but the largest must still be small enough so that the ink will be held therein by capillary action and friction to the end that it will be transferred evenly from plate to the material being printed.

There are a number of ways of carrying out the present invention but I prefer to produce the novel printing plate as follows:

Having selected a photograph, I place this on the copy board of a copying camera, and by means of the usual photographic operations produce a negative thereof, either on paper or on glass. Thus I obtain a photograph in negative form, the high lights of the original being represented by dark areas, the middle tones by less pronounced shades, and the shadows by white areas. It is from this negative that I carry out the next operation, which will give a screen positive in which the high lights will be represented by small opaque dots, the middle tones by larger dots, and the shadows by very large opaque dots,

which, however, do not overlap or touch in any part.

This screen positive, in which the dots are approximately diamond-shaped, appears as shown in Figure 2. Referring to the diagram, dot 2 represents a large shadow dot, formed by the light action from the white areas of the negative, and progressively, proceeding toward the right, may be seen the middle tone dots 3, and high light dots 4, the latter merely points, as compared with the shadow dot 2.

This screen positive is produced as follows:

The negative copy of the original is placed before a camera in which a half-tone screen has been established at a suitable distance in front of a sensitive photographic plate. This distance is generally much less than in the usual half-tone operations, being preferably about one-half of that customarily employed in half-tone work. In the lens chamber reserved for stops as employed in the half-tone process I place a diamond-shaped stop with the sides parallel to the lines of the half-tone screen. With this stop in place, and by altering the distance of the screen from the sensitive plate, I readily determine a screen distance that, upon making the exposure, gives a dot formation corresponding precisely to the tone gradations of the original copy. That is to say, small dots will appear as high-light dots, larger dots representative of the middle tones, and very large dots representative of the shadows. Further, if the exposure has been timed correctly, these large shadow dots will not be joined or connected in any part, but will be more or less diamond-shaped, and with parallel sides.

Referring to the drawing. Study of the shadow areas of Figure 1, illustrating a screen positive thus produced will show that I have produced a grid of transparent area, isolating the relatively large dots, and that proceeding toward the middle tones this grid becomes wider between dots, and the dots smaller. In the extreme high lights the grid has become very heavy and the lines correspondingly wide, with the intervening dots relatively small.

As a further provision for the control of tone gradation, I am able by screen adjustment, and in development of the sensitive plate, to make the relatively large dots very opaque, while rendering the small high light dots more or less translucent, or, in the highest lights, absent entirely. This procedure, as will be explained later, is most important in making my process highly flexible and useful for the purposes set forth.

Having produced my screen positive, as illustrated by Figure 1, I now proceed along one of two courses, according to the effect that I desire to secure. If I am seeking a precise and exact reproduction of the photograph copy, and do not intend to alter largely the tone values thereof, I proceed as follows:

I place the screen positive, shown in Figure 1, in a photographic printing frame, or in the so-called "step and repeat" machine, and print it down photographically on a sensitive plate, thereby transforming it into a negative. In this negative the diamond-shaped dots will appear as transparent areas and the surrounding grid as an opaque network. This formation is shown in Figure 3.

I now proceed to sensitize a smooth metal plate, with a light sensitive solution, of which bichromated glue, as commonly used in photo-engraving, is an excellent example. However,

there are numerous compounds of the kind, that can be used with equal success. Upon this sensitized plate I impose my screen negative, as indicated in Figure 3, and submit the whole to the action of light. After a suitable exposure the sensitized plate is developed in water. If bichromated glue has been used, the glue that has not been acted upon by the light will wash away, leaving a dot formation corresponding to the transparent dot areas of the negative.

The plate is then heated until the glue dots are "burned in" or carbonized, rendering them similar to the enamel dots of a half-tone plate that has been prepared for etching, but with one important exception. Whereas, in the true half-tone formation, the shadows will consist of large areas produced by overlapping dots, giving so-called "solids", in my plate the shadow dots will be found isolated by narrow lines of exposed metal, forming a distinct grid or mesh effect. The plate thus produced I style a "master plate". From it, as will be explained, I can produce an infinite number of printing plates of exactly the same size and printing value.

It will be appreciated that I have created a screen effect similar to that seen in screen intaglio, but with tone values determined largely by the size of the dot between the walls of the screen, rather than by the depth of the cell itself. The advantage of this formation will be pointed out hereinafter.

Referring again to the master plate, I proceed as follows:

The plate is rubbed over with a compound that will prevent adherence of any metal that may be deposited thereon. Wax may be used for this purpose, although there are various methods for accomplishing this purpose. Having so prepared the plate, I insert it in an electroplating bath, suitably prepared for the metal that is to be deposited, and proceed to form a relatively thin coating of metal over the master plate. No metal will form over the enamel dots, which are non-conducting, but it will form rapidly over those parts corresponding to the grid of varying width of line.

When a deposit of the required thickness is formed I remove the master plate from the bath and strip away the deposited plate. The latter will be found to be a perfect representation of my photographic negative as disclosed by Figure 3. The dots will be holes or ducts through the plate, and corresponding to the transparent dots of the negative.

The master plate may be returned immediately to the plating bath and another plate prepared for stripping away. This operation may be continued indefinitely, making as many duplicated plates as required.

The stripped plate is now ready for printing. It is preferably placed around a hollow metal cylinder 5, the surface of which is perforated by many small holes 6, which are covered in turn by a porous blanket 7 of suitable material. It is over this blanket that the printing plate is secured, encircling the cylinder and closely fastened thereto by suitable gripping and locking devices 8.

Ink is introduced into the hollow cylinder. It quickly percolates through the porous blanket, and reaches the inner surface of the printing plate, filling the minute ducts. As the cylinder is set revolving, with paper passing between it and an impression roller, capillary attraction draws the ink through the ducts, and results in

printing upon the paper. However, it may be desirable to exercise control over the rate of ink flow with relation to press speed and impression pressure. This I may accomplish by making the 5 ink-containing cylinder air-tight, and by connecting it with an air pump by means of a passage 10 through the axle 11 of the cylinder. I can thus control the pressure of the air inside of the cylinder, either introducing air to raise the 10 pressure above that of the atmosphere, or actually reducing it in order to create a partial vacuum. It will be readily apparent that by this means I have very complete and delicate control over the ink flow.

15 The printing plate having minute ducts or passages for the ink may also be produced by reproducing by well known photographic methods the ducts in a resist applied to a thin metal plate so that the metal is exposed at the multiplicity of 20 points at which the ducts are to be formed. The thin metal plate may then be etched in known manner, the etching being carried forward until ducts are formed extending completely through the metal at all exposed points.

25 Having described my method of producing a printing plate where a precise duplication of the original is required, I shall now describe an alternative method followed where a change in tone value or contrast is demanded.

30 Returning to my screen positive as shown in Figure 1, instead of transforming this into a negative, I proceed as follows: A piece of carbon tissue as commonly employed in the photogravure process is sensitized with potassium bichromate 35 and dried in the usual manner. It is then placed in a printing frame beneath the screen positive, and a print of the latter made upon the tissue. This action of the light is continued until the gelatine has been rendered insoluble for a 40 considerable depth around the large shadow dots, but without actually penetrating these dots, or creeping to any appreciable extent beneath them. At the same time, incursion of light will occur around the much smaller high light dots, and 45 the gelatine beneath these dots will be rendered more or less insoluble.

I now transfer my carbon tissue in the usual manner to a metal plate, develop in warm water, and dry. Inspection will show the areas corresponding to the large shadow dots almost, if not 50 entirely, devoid of gelatine covering, while in the high light areas considerable gelatine will be found at the bottom of the dots.

I now proceed to etch with a heavy solution of 55 perchloride of iron, of 41 or 49 Baumé. This solution will readily penetrate the shadow dot areas, and etch corresponding depressions in the metal, but as the high light dots are approached the etching will cease, for the heavy perchloride 60 will not penetrate the gelatine skin at the bottom of the high light depressions. Consequently, by resorting to a perchloride of slightly less density, say 36 Baumé I may etch the high light areas as I see fit, stopping the action when I consider the 65 area and depth of the dots sufficient. Thus I may control the relative contrast of my picture, regardless of the original.

With this etching completed, I wash away the 70 gelatine, and dry what is now a master plate, save for one remaining operation. This consists in filling in the etched depressions or cells of varying area with a non-conducting and acid resisting compound, of which many combinations are possible. Wax works very well, and if rubbed 75 over the plate soon fills the depressions. The

surplus may be readily polished from the surrounding surfaces. I now proceed as in the first operation, treating the plate in order that a deposited metal may not adhere thereto, and plating thereon and stripping away the relatively 5 thin coatings as heretofore described.

Type matter in my new process is handled with the utmost ease, and in practically the same manner as pictures, although even more easily. A negative of the type matter is made, and between 10 it and the sensitized metal plate, a transparent medium carrying a screen of narrow opaque lines is interposed. This gives a grid effect throughout the type matter, as printed down upon the master plate, and the result is identical with the 15 pictorial process save that all ducts for the type matter are of the same size, thus giving a uniform printing throughout.

With my method of supplying ink to the printing surface by small holes or ducts, graded as 20 to size and arrangement to print the desired impression, and controlling the supply of ink through the openings by air pressure or the like, any desired amount of ink may be supplied to the printing surface, whereby to give either a thin or a 25 heavy coat to the printed matter. With other methods of printing, the amount of ink which the printing surface will take is restricted, and only one shade of printing can be produced with a given plate, except that the printed matter be 30 run through the press a second or third time.

This application is a division of my application Serial No. 239,388, filed December 12, 1927.

The invention may be embodied in other specific forms without departing from the spirit or 35 essential characteristics thereof. The present embodiment is therefore to be considered in all respects as illustrative and not restrictive, the scope of the invention being indicated by the appended claims rather than by the foregoing 40 description, and all changes which come within the meaning and range of equivalency of the claims are therefore intended to be embraced therein.

What is claimed and desired to be secured by 45 United States Letters Patent is:—

1. A printing or stencil plate in which the printing areas consist of separate and distinct dot-like openings in the plate of various sizes to govern the tone value of the printing, the maximum dimension of any opening being smaller than the distance between the center of any two openings in the plate and in which non-printing areas completely surround each and every opening and isolate said opening from adjacent openings in the shadows as well as every other part 55 of the plate.

2. A printing or stencil plate comprising a metal structure having printing areas consisting of separate and distinct dot-like openings in the 60 structure of various sizes, adjacent openings in the shadows as well as in other parts of the structure being separated from each other and each opening being completely bounded by continuous and uninterrupted non-printing areas, the maximum dimension of any opening being smaller than the distance between the centers of any two openings in the plate, whereby the variations in the tone value of the printing are obtained by varying the size of said openings and the dimensions of said non-printing areas.

3. A printing or stencil plate consisting of a metal body having non-printing areas in a single plane and printing areas formed by means of separated and distinct dot-like openings 75

- formed in said plate of varying sizes, every dot, including those in the shadows being separated from adjacent dots by a non-printing area and having a maximum dimension smaller than the distance between the centers of any two openings in the plate, the variation in the tone value of the printing being obtained by varying the size of said openings and the dimensions of said non-printing areas.
10. 4. A printing or stencil plate consisting of non-printing areas in the same plane and printing areas consisting of separate and distinct dot-like openings of various sizes formed in the plate from said plane, the larger openings corresponding in position to the darkest parts of the printing and being each completely separated from adjacent larger openings by a non-printing area, the maximum dimension of any opening being smaller than the distance between the centers of any two openings in the plate, whereby the variation in tone value of the printing is obtained by varying the size of said openings and the dimensions of the non-printing areas that completely surround each of said openings.
15. 5. A printing plate consisting of a metal body

having non-printing areas formed by the plane of its surface, and printing areas formed by means of separated and distinct dot-like openings of various sizes formed in said plate, every dot-like opening being completely isolated and separated from adjacent dot-like openings by a non-printing area and having a maximum dimension smaller than the distance between the centers of any two openings in the plate whereby friction and capillary action in said dot-like 10 openings may be utilized to control the even transfer of ink from said plate.

6. A printing plate consisting of a metal body having non-printing areas formed by the plane of its surface, and printing areas formed by 15 means of separated and distinct dot-like openings of various sizes formed in said plate, every dot-like opening being completely isolated and separated from adjacent dot-like openings by a non-printing area and having a maximum dimension smaller than the distance between the centers of any two openings in the plate, the non-printing areas being arranged so as to be parallel to each other regardless of their width.

ERNEST S. BALLARD. 25
